UNITED STATES PATENT OFFICE.

CHARLES H. HESS, OF ZANESVILLE, OHIO, ASSIGNOR TO THE KEARNS-GORSUCH BOTTLE COMPANY, OF SAME PLACE.

DESIGN FOR A BOTTLE.

SPECIFICATION forming part of Design No. 34,957, dated August 20, 1901.

Application filed July 26, 1901. Serial No. 69,855. Term of patent 7 years.

To all whom it may concern:

Be it known that I, CHARLES H. HESS, a citizen of the United States, residing at Zanesville, in the county of Muskingum and State of Ohio, have invented and produced a new and original Design for a Bottle, of which the following is a specification.

This invention relates to bottles; and the object thereof is to provide a new, original, and useful design for articles of this character.

The leading features of this invention reside in a body which is substantially elliptical in cross-section and comprises convexedly curved opposite side walls joined together by flattened end walls, said side and end walls terminating at their upper ends in an upwardly-tapering breast, from which projects a centrally-disposed neck. The breast is provided with flutes or ribs that radiate from the neck, and the body is also provided with a ring of flutes or ribs that are located contiguous to the lower end and extend longitudinally of said body.

In the drawings, Figure 1 is a perspective view of a bottle embodying the present de-

sign. Fig. 2 is a cross-sectional view through the same.

As will be seen by reference to the drawings, the body is substantially elliptical in cross-section, comprising convexedly curved opposite side walls 10, joined together by flattened end walls 11, the upper ends of said walls terminating in a tapering breast 12, from which projects a centrally-disposed neck 13. The breast is provided on its exposed face with ribs or flutes 14, that radiate from the neck, and the body is provided contiguous to its lower end with a ring 15, of flutes or beads, which are located longitudinally of said body.

Having thus described my invention, what I claim as new, and desire to secure by Letters Patent, is—

The design for a bottle as herein shown and described.

In testimony that I claim the foregoing as my own I have hereto affixed my signature in the presence of two witnesses.

CHARLES H. HESS.

Witnesses:

NOAH E. BAGLEY,

ROBERT H. MCFARLAND.
